[57] **ABSTRACT**

A process for frequency modulation of binary messages in which the variables 0 and 1 are represented by signals of respective frequencies f_0 and f_1 differing by frequency Δf . The process is characterized in that, to prevent undesirable phase modulation during the switching from one frequency to the other, frequency f_1 is related to frequency f_0 by deriving the signal of frequency f_1 from a carrier wave form at the frequency f_0 through modulation of such frequency f_0 to obtain a single sideband by means of a signal of frequency Δf which determines the rate of the switching intervals of the binary message. The apparatus comprises a first generator providing a carrier wave form of frequency f_0 , a first phase shifting circuit providing two first signals of frequency f_0 shifted by 90° , a second generator providing a signal of frequency Δf , a second phase shifting circuit providing two second signals phased 90° from each other, two modulators for amplitude modulating the two first signals by the two second signals respectively, an adding circuit for adding the outputs of said two modulators and having means for suppressing one of the sidebands and the carrier waveform so as to generate a signal of frequency f_1 , an electronic switching means operated at the frequency Δf or a submultiple thereof for switching the signals of frequencies f_0 and f_1 in accordance with the message to be transmitted.

**PROCESS AND APPARATUS FOR TRANSMISSION
OF BINARY MESSAGES BY SYNCHRONIZED
FREQUENCY SHIFT KEYING**

This invention relates to a process and an apparatus for frequency modulation of binary messages.

In the transmission of binary messages, it is commonly known to use signals of different frequencies f_0 and f_1 , representing respectively the binary variables 0 and 1. When such signals are provided by separate generators, the relative phase of the signals varies in an undetermined fashion at the time of switching from one generator to the other. There is thus produced a phase modulation which hinders the spectrum of the frequencies used and may cause perturbations.

It is an object of the present invention to eliminate the above mentioned undesirable phase modulation by providing a switching in which the relative phase of the signals does not change.

When the frequency of a sinusoidal oscillation goes suddenly without phase discontinuity from the value f_0 to the value $f_1 = f_0 + \Delta f$, taking as a time origin the switching moment, the signal obtained is:

$$e_1(t) = E_0 \cos 2\pi (f_0 t + \Delta f t)$$

starting from time $t = 0$.

If it is desired to prevent any phase discontinuity at the time of the return of the signal at frequency f_0 , it is necessary to wait until the signal $e_1(t)$ is in phase with the signal $e_0(t) = E_0 \cos 2\pi f_0 t$, which happens at the time $T = 1/\Delta f$. By passing from one frequency to the other at the speed Δf , it is then possible to prevent the phase discontinuities.

In accordance with the invention, the frequency f_1 is related to the frequency f_0 by deriving the signal of frequency f_1 from a carrier wave form at frequency f_0 through modulation of such carrier to obtain a single sideband signal by means of a signal of frequency Δf which determines the rate of the transition moments of the binary message.

The apparatus, in accordance with the invention, comprises a first generator providing a carrier wave of frequency f_0 , a first phase shifting circuit providing two first signals of frequency f_0 shifted from each other by 90° , a second generator providing a signal of frequency Δf , a second phase shifting circuit providing two second signals of frequency Δf shifted from each other by 90° , a second generator for amplitude modulation of the two first signals by the two second signals respectively, an adding circuit for adding the outputs of the two modulators, means forming part of such modulators for suppressing one sideband and the carrier wave so as to obtain a signal of frequency f_1 , and an electronic switching device operated at the frequency Δf or at a submultiple thereof to switch the signals of frequencies f_0 and f_1 , depending upon the message to be transmitted.

The invention will now be disclosed with reference to a preferred embodiment thereof and to the accompanying drawings in which:

FIG. 1 illustrates two signals of frequencies f_0 and f_1 representing the binary variables 0 and 1 respectively, wherein phase modulation occurs at the time of switching from frequency f_0 to frequency f_1 ;

FIG. 2 illustrates the same signals at frequencies f_0 and f_1 respectively, wherein no phase modulation occurs at the time of switching from one frequency to the other; and

FIG. 3 illustrates a circuit for preventing the phase modulation of FIG. 1 and providing a switching from one frequency to the other, such as illustrated in FIG. 2.

FIG. 1 illustrates an example of phase modulation after a time interval T of the generation of the signal of frequency f_0 which is followed by the signal of frequency f_1 .

FIG. 2 illustrates an example wherein no phase modulation is generated at the time of switching from frequency f_0 to frequency f_1 .

FIG. 3 illustrates a preferred embodiment of a circuit for the transmission of binary messages using two frequencies f_0 and f_1 representing respectively the logic variables 0 and 1. Such a circuit comprises a generator 1 providing a signal of frequency f_0 which is applied to a phase shifter 2 providing two signals (f_0) and $(f_0) \pi/2$ of frequency f_0 shifted from each other by $\pi/2$ radians.

These two signals are applied to two modulators 3 and 4 equipped respectively with transistors 3 and 4 which amplitude modulate by multiplication the signals (f_0) and $(f_0) \pi/2$ by the signals $m(t)_0$ and $m(t) \pi/2$ of frequency $\Delta f = f_1 - f_0$, shifted between each other by an angle $\pi/2$. The last mentioned signals are generated by a phase shifting circuit 5 fed by a generator 6. These signals are applied to the collectors of transistors 3 and 4 through respective resistors 7 and 8.

The signals at the collectors of transistors 3 and 4 are applied to an adding circuit 9. It may be demonstrated that the output of adding circuit 9 may, in such conditions, generate a signal containing the upper sideband only of the carrier wave at frequency f_0 modulated at the frequency Δf , and wherein the carrier wave is suppressed. There is so obtained a signal of frequency $f_0 + \Delta f$, that is of frequency f_1 . The signals of frequencies f_0 and f_1 are applied to an inverter equipped with transistors 10 and 11 controlled respectively, at the frequency Δf or a submultiple thereof, according to the

binary message M to be transmitted or its complement M' . The inverter provides an output signal s which is used for the transmission of the message. It may be easily understood that, from what has been said before, the switching from one frequency to the other may be done without phase modulation. Such switching is done at the passage to zero of the signal $m(t) \pi/2$ which provides the signals R determining the rate of the succession of the transition moments of the binary message.

In the case in which a rate of succession of the transition moments of the binary message would be equal to half the inverse of frequency Δf , there would be obtained each time a phase inversion which could be used to realize a transmission by phase modulation at 180° . However, a discriminator must be used for generating a phase opposite to the phase detected one time out of two, and it is for each of the two frequencies.

I claim:

1. Process for transmission of binary messages by frequency shift keying synchronized with the transitions of the messages, whereby the two frequencies used are tied together by using single sideband modulation of a carrier wave in order to avoid undesirable phase modulation, comprising the step of selecting respectively, for the two frequencies, the carrier wave and one of the two sidebands of said carrier wave modulated by a signal having a frequency equal to the difference of said two frequencies.

2. In an apparatus for transmission of binary messages by frequency shift keying synchronized with the transitions of the messages, including a carrier wave generator, a low frequency signal generator for modulating said carrier wave, and means responsive to said carrier wave generator and to said low frequency signal generator for generating one single sideband signal, the

improvement comprising means for switching, at the output terminals of such apparatus, said carrier wave and said single sideband signals according to the data of the message to be transmitted, and means for operating said switching means at the rate of said low frequency signal.
